[57] ABSTRACT

An aircraft fuselage defining a downwardly opening centrally disposed air cushion containing chamber bound along its opposite sides by upstanding longitudinally extending plenum chambers. Opposite side high bypass turbo engine pods are supported outwardly of the plenum chambers and structure is provided for variably bleeding the bypass air from the engine pods directly into the plenum chambers which in turn include lower outlets spaced longitudinally therealong opening at least substantially directly into the air cushion containing chamber.

AIRPLANE WITH AIR CUSHION LANDING GEAR

The airplane of the instant invention includes a fuselage whose lower central area defines a downwardly opening chamber positioned closely adjacent the ground when the airplane is supported from its landing wheels. The chamber includes peripherally spaced air inlet means through which air under pressure may be admitted at high velocity and the airplane includes a plurality of high bypass turbo fan engines as propulsion units and the bypass air from these engines is ducted almost directly to the inlets for the air cushion chamber. Accordingly, the engines of the aircraft serve the dual function of providing a propulsive force for the aircraft and also as a means for supplying large quantities of air under pressure to the air cushion chamber whereby at least during takeoff operations the bypass air from the engines may be utilized to form a supporting air cushion beneath the fuselage of the aircraft in order to lift the latter clear of its landing wheels so as to greatly reduce rolling friction of the multiple landing wheels on the runway and thus enable the aircraft to attain flying speed more quickly.

It is the main object of this invention to provide an aircraft with improved landing gear which may function both during takeoff and landing as well as taxiing operations and may be utilized to cushion landing shock, reduce rolling friction during takeoff and also facilitate tight maneuvering operations when taxiing.

A further object of this invention is to provide an aircraft in accordance with the immediately preceding object and constructed in a manner whereby it may also be guided along a ground supported track structure and/or an elevated monorail structure for transport of the aircraft to and from a landing area distant from an urban area in which the aircraft may be boarded or passengers may disembark the aircraft.

Another object of this invention is to provide an improved air cushion supplemented landing gear system for aircraft designed to utilize existing power plants for supplying compressed air to the air cushion forming structure of the invention.

Still another object of this invention, in accordance with the immediately preceding object, is to provide an aircraft provided with propulsion units which will not only serve to propel the aircraft but which may also be utilized to provide the required air under pressure for operating the air cushion forming structure of the aircraft.

Another important object of this invention is to provide an aircraft whose dual function engines are positioned relative to the air cushion forming structure in a manner such that the air under pressure provided by the dual purpose engines may be ducted to the air cushion forming structure in an efficient manner with little loss of air velocity and pressure.

A final object of this invention is to provide an air cushion supplemented aircraft landing gear assembly which will conform to conventional forms of manufacture, be of relatively simple construction and easy to operate so as to provide a device that will be economically feasible, durable and readily operable with a minimum of sophisticated controls.

These together with other objects and advantages which will become subsequently apparent reside in the details of construction and operation as more fully hereinafter described and claimed, reference being had to the accompanying drawings forming a part hereof, wherein like numerals refer to like parts throughout, and in which:

FIG. 1 is a side elevational view of an aircraft constructed in accordance with the present invention;

FIG. 2 is a fragmentary front elevational view of the aircraft;

FIG. 3 is a fragmentary bottom plan view of the aircraft on somewhat of an enlarged scale;

FIG. 4 is an enlarged fragmentary horizontal sectional view taken substantially upon the plane indicated by the section line 4-4 of FIG. 1;

FIG. 5 is a fragmentary enlarged transverse vertical sectional view taken substantially upon the plane indicated by the section line 5-5 of FIG. 1;

FIG. 6 is a fragmentary enlarged transverse vertical sectional view similar to FIG. 5 but illustrating the manner in which the aircraft may be aligned with a ground track for movement therealong;

FIG. 7 is a view similar to FIG. 6 but with the landing wheels of the aircraft retracted upwardly so as to lower the fuselage of the aircraft downwardly upon the ground track; and

FIG. 8 is a fragmentary side elevational view of the aircraft supported from a monorail structure into which the ground track illustrated in FIGS. 6 and 7 may gradually merge.

Referring now more specifically to the drawings, the numeral 10 generally designates an aircraft constructed in accordance with the present invention. The aircraft 10 includes a high wing structure referred to in general by the reference numeral 12, a low slung fuselage assembly referred to in general by the reference numeral 14 and a tail assembly referred to in general by the reference numeral 16 which includes a vertical rudder 18 having a horizontal stabilizer 20 at its upper end.

As can best be seen from a comparison of FIGS. 3 and 5 of the drawings, the fuselage assembly 14 includes a pair of upstanding opposite side and longitudinally extending plenum chambers 22 whose inner walls are defined by the opposite side walls 24 of the fuselage assembly 14. A downwardly opening chamber 26 is defined between the lower peripheral portions of the sides or side walls 24 and is closed at its upper extremity by means of a bottom wall 28 extending between the sides 24.

A pair of transversely spaced sets of longitudinally aligned hydraulic cylinders 32 are secured to and disposed from the bottom wall 28. The cylinders 32 include depending piston rod portions 34 on whose lower ends cross axle shafts 36 are mounted. Each of the cross axle shafts 36 has three closely spaced wheels 38 mounted on each of its opposite ends

and it is to be noted that the hydraulic cylinders 32 are of the double acting type whereby the axle shafts 36 may be raised and lowered relative to the lower marginal edge portions of the sides 24. In addition, any suitable means (not shown) may be provided for rotating the piston rods 34 whereby the axle shafts 36 may be angularly displaced about vertical axes for steering the wheels 38.

From FIG. 3 of the drawings, it will be noted that four axle shafts 36 are provided on each side of the fuselage assembly 14 and the means (not shown) by which the piston rods 34 may be rotated shall be operable to simultaneously rotate the piston rods 34 disposed fore-and-aft of the longitudinal center of the chamber 26 in opposite directions. Also, the means for rotating the piston rods 34 may be further operable to rotate all of the piston rods 34 in the same direction whereby the wheels 38 may be obliquely arranged for landing and takeoff in cross winds.

The lower portion of the chamber 26 is separated from the upper portion thereof by means of a horizontal partition 40 also secured between the side walls 24. However, the partition 40 includes openings 42 formed therethrough by which the wheels 36 may be extended to positions below the partition 40 and retracted to positions above the partition 40.

The lower ends of the plenum chambers 22 are rounded as at 44 and the upwardly convergent inner wall portions 46 thereof have a plurality of longitudinally spaced outlet openings 48 formed therein opening inwardly and downwardly into the lower portion of the chamber 26.

A pair of engine pods or housings referred to in general by the reference numerals 50 are supported from the upper portions of the outer walls 52 of the plenum chambers 22 and each of the pods 50 has a high bypass turbo fan engine generally referred to by the reference numeral 54 mounted therein. The high bypass turbo fan engines may be of any desirable type such as the T55 turbo fan engine manufactured by Avco, Lycoming Division. The turbo fan engines 54 include a fan assembly 56 which is front-mounted on the engine 54 and mated to the power turbine thereof through a center shaft. The forward ends of the pods 50 are open as are the rear ends thereof, but the rear ends of the pods 50 include horizon-

tally swingable shutters 58 having semicircular cutouts 60 formed in their free swinging edge portions. The shutters 60 are swingable by any suitable means (not shown) from the full open positions illustrated in solid lines in FIG. 4 of the drawings to fully closed positions such as those illustrated in phantom lines in FIG. 4 of the drawings with the semicircular openings or recesses 60 formed in the shutters 58 closely embracing opposite sides of the outlet pipe 62 of the engine 54.

A pair of registered openings 64 and 66 are formed through the inner wall 68 of each pod 50 and the adjacent outer wall 52 of the corresponding plenum chamber 22. Accordingly, when the shutters 58 are closed, the discharge of air from the fan assemblies 56 is ducted directly into the plenum chambers 22 and from the latter through the openings 48 into the opposite side portions of the lower portion of the chamber 26 disposed below the partition 40.

A pair of shutters referred to in general by the reference numeral 70 are hingedly supported from the plenum chambers 22 as at 72 and are swingable between the solid positions thereof illustrated in FIG. 5 of the drawings closing the opening 66 and the phantom line positions thereof illustrated in FIG. 5 of the drawings allowing the free passage of air from the interiors of the pods 50 into the plenum chambers 22. The shutters 70 are actuated by means of double acting fluid motors 74 connected between the sides 24 of the fuselage assembly 14 and the shutters 70.

The lowermost positions of the wheels 38 illustrated in FIG. 5 of the drawings are the positions assumed by the wheels when the hydraulic cylinders 32 are fully extended. The wheels 38 are positioned in this manner when the aircraft 10 is being taxied. Further, when the hydraulic cylinders 32 are actuated to raise the wheels 38 so that their lower peripheral portions are generally horizontally aligned with the partition 40, the wheels 38 are in the positions thereof which are assumed during flight of the aircraft 10. Further, when the wheels 38 are positioned halfway between their uppermost and lowermost positions with the lower peripheral portions of the wheels 38 projecting only slightly beneath the lower extremities of the plenum chambers 22, the wheels 38 are positioned as they will be when the air cushion formed in the lower extremity of the chamber 26 is operative. In this intermediate position of the wheels 38, the aircraft 10 may taxi and be at least partially supported by the air cushion formed in the lower extremity of the chamber 26 below the partition 40. In addition, this intermediate position of the wheels 38 may also be maintained during takeoff of the aircraft 10 whereby the air cushion being formed will be spaced closely adjacent the ground and will be more effective to reduce the amount of weight of the aircraft 10 supported from the wheels 38 during takeoff of the aircraft 10. Also, the wheels 38 are positioned in their intermediate positions during tight maneuvering of the aircraft 10 on the ground during taxiing so as to reduce the amount of weight supported by the wheels 38.

It is believed readily apparent that the bypass air being formed by the fan assemblies 56 may be partially throttled or fully throttled so as to be partially or fully ducted into the plenum chambers 22. Further, the shutters 58 may be fully opened and the shutters 70 may be fully closed whereby no air will be ducted into the plenum chambers 22.

Further, in order to assist in braking and maneuvering on the ground, the forward end portions of the outer walls 52 include outlet openings 80 with which pivotally supported control flaps 82 are operatively associated. The flaps 82 are independently controllable by any suitable power means and may be opened to retard forward movement of the aircraft 10 or to assist in ground maneuvering of the aircraft.

It may further be seen from the drawings that the opposite side walls 24 of the fuselage assembly 14 include openings 84 directly communicating the chamber 26 with the interiors of the plenum chambers 22. The openings 84 are disposed above the partition 40 in which the openings 42 are formed and serve to admit air under pressure into the area immediately beneath the partition 40 by way of the chamber 26 through the open-

ing 42. Further, the lower extremities of the plenum chambers 22 are provided with longitudinally spaced rollers 86 journaled for rotation about vertical axes and including inner peripheral portions which project into the area beneath the partition 40 between the plenum chambers 22. The lower extremities of the plenum chambers 22 in which the rollers 86 are journaled are sealed from the portions of the plenum chambers 22 disposed thereabove by means of partitions 88.

With attention now invited more specifically to FIGS. 6 and 7 of the drawings, it may be seen that when the wheels 38 are lowered the aircraft 10 may be moved obliquely across a landing surface 90 having a pair of upwardly opening parallel grooves 92 formed therein between which a ground track 94 is defined until the aircraft 10 is vertically registered with the ground track 94. Thereafter, while an air cushion is maintained beneath the partition 40, the wheels 38 may be upwardly retracted so as to lower the aircraft 10 gently onto the ground track 94 as the pressure of the air cushion is gradually reduced. At this point, the wheels 38 will rest upon the upper surface 96 of the ground track 94 with the rollers 86 engaged with the opposite side edges 98 of the ground track 96. Then, the aircraft 10 may proceed either toward or away from a landing area relative to a distant urban area in which the aircraft may be boarded or passengers may disembark from the aircraft. Thus, it is possible for the aircraft 10 to land at an airport some distance from an urban area and move along the ground track 94 to the urban area at which the passengers may disembark the aircraft. Of course, the aircraft 10 may then be boarded by other passengers and move along a similar return ground track to the distant airport from which the aircraft 10 may take off.

With attention now invited more specifically to FIG. 8 of the drawings it may be seen that the aircraft 10 is disposed upon an elevated monorail structure 100 into which the ground track 94 may gradually merge in the event the topography of the ground between the airport and the distant urban area dictates that some sections, at least, of an elevated monorail structure be used in lieu of a ground level ground track.

The foregoing is considered as illustrative only of the principles of the invention. Further, since numerous modifications and changes will readily occur to those skilled in the art, it is not desired to limit the invention to the exact construction and operation shown and described, and accordingly all suitable modifications and equivalents may be resorted to, falling within the scope of the invention as claimed.

What is claimed as new is as follows:

1. An elongated vehicle body defining a downwardly opening centrally disposed air cushion containing cavity bound along opposite sides by longitudinally extending plenum chambers a pair of engine pods supported adjacent and outwardly of said plenum chambers, propulsion engines mounted in said engine pods and including driven high capacity air compressing components, means operable to variably bleed compressed air from said pods substantially directly into said plenum chambers, and means operable to substantially directly discharge air from said plenum chambers into said air cushion containing cavity, a track including a generally planar upper longitudinal surface and generally parallel opposite side surfaces depending from the opposite longitudinal marginal edges of said upper surface, said vehicle body being disposed on said track with the inner opposing lower marginal inner surface portions of said plenum chambers closely embracing said side surfaces, said vehicle body including a plurality of longitudinally spaced sets of transversely aligned and closely spaced ground engaging wheels whose lower peripheral portions project slightly below the undersurface portions of said body, said sets of wheels being disposed in and at least partially dividing the interior of said cavity into a plurality of longitudinally spaced cavity segments.
2. The combination of claim 1 wherein said lower marginal edge portions of said plenum chambers include longitudinally spaced rollers journaled for rotation about upstanding axes

and including inner peripheral edge portions projecting into said cavity through said opposing lower marginal inner surface portions of said plenum chambers for rollers engagement with said opposite side surfaces.

3. The combination of claim 1 including means supporting said sets of wheels for vertical shifting relative to said vehicle body between limit positions with the lower peripheral portions of said wheels spaced above and below a horizontal plane containing the lower extremities of said plenum chambers.

4. The combination of claim 1 wherein said track is defined in a planar surface by means of a pair of parallel grooves defined in said upper surface between which said longitudinal surface is defined and whose adjacent side walls define said parallel opposite side surfaces.

5. The combination of claim 1 wherein said track comprises an elevated monorail structure.

6. The combination of claim 5 wherein said lower marginal edge portions of said plenum chambers include longitudinally spaced rollers journaled for rotation about upstanding axes and including inner peripheral edge portions projecting into said cavity through said opposing lower marginal inner surface portions of said plenum chambers for rolling engagement with said opposite side surfaces.

7. An elongated vehicle body defining a downwardly opening centrally disposed air cushion containing cavity bound along opposite sides by longitudinally extending plenum chambers a pair of engine pods supported adjacent and outwardly of said plenum chambers, propulsion engines mounted in said engine pods and including driven high capacity air compressing components, means operable to variably bleed compressed air from said pods substantially directly into said plenum chambers, and means operable to substantially directly discharge air from said plenum chambers into said air cushion containing cavity, a track including a generally planar upper longitudinal surface and generally parallel opposite side surfaces depending from the opposite longitudinal marginal edges of said upper surface, said vehicle body being disposed on said track with the inner opposing lower marginal inner surface portions of said plenum chambers closely embracing said side surfaces, said track is defined in a planar surface by means of a pair of parallel grooves defined in said upper sur-

face between which said longitudinal surface is defined and whose adjacent side walls define said parallel opposite side surfaces, said vehicle body including a plurality of longitudinally spaced sets of transversely aligned and closely spaced

5 ground engaging wheels whose lower peripheral portions project slightly below the undersurface portions of said body, said sets of wheels being disposed in and at least partially dividing the interior of said cavity into a plurality of longitudinally spaced cavity segments.

10 8. The combination of claim 7 including means supporting said sets of wheels for vertical shifting relative to said vehicle body between limit positions with the lower peripheral portions of said wheels spaced above and below a horizontal plane containing the lower extremities of said plenum chambers.

15 9. An elongated vehicle body defining a downwardly opening centrally disposed air cushion containing cavity, means carried by said vehicle for discharging compressed air into said cavity, a track including a generally planar upper longitudinal surface, said vehicle body being disposed on said upper surface and including a plurality of longitudinally spaced sets of transversely aligned and closely spaced ground engaging wheels whose lower peripheral portions project slightly below the undersurface portions of said body, said sets of wheels 20 being disposed in and at least partially dividing the interior of said cavity into a plurality of longitudinally spaced cavity segments.

25 10. The combination of claim 9 including means supporting said wheels for vertical shifting relative to said vehicle body 30 between limit positions with the lower peripheral portions of said wheels spaced above and below a horizontal plane containing the lower extremities of said body.

35 11. The combination of claim 9 wherein said track includes generally parallel opposite side surfaces depending from the opposite longitudinal marginal edges of said upper surface, said vehicle body including parallel downwardly projecting lower opposite side portions, said opposite side portions including longitudinally spaced rollers journaled for rotation about upstanding axes and including inner peripheral portions 40 projecting into said cavity for rolling engagement with said opposite side surfaces.
